TROLLING PLATE ATTACHMENT

Edward R. Kotike, St. Paul, Minn.

Application June 26, 1946, Serial No. 679,318

9 Claims. (Cl. 170—135)

1

The present invention relates to trolling plates and more particularly to an arrangement providing a trolling plate which will be readily attachable to and detachable from substantially any type of boat propeller and which can be fixed in operative position securely against loss or undesired separation.

In the type of fishing operation known as trolling, when practiced with a motorboat, it is necessary to propel the boat at a rate of speed which is generally somewhat lower than the minimum to which the ordinary gasoline engine can be throttled down without stalling. Such low speeds are commonly obtained by the use of some retarding means. The most successful of these means comprise baffles associated with the propeller to reduce the propelling effect, and it is to this type of structure that the present invention relates.

A primary requisite of all such baffles is the capacity to mount and dismount them with a minimum of difficulty and delay and the capacity to fix them securely in mounted position so that they will not become accidentally disengaged and lost.

The present invention provides an attachment having the foregoing desirable properties, along with others, including simplicity of design, economy of manufacture, durability of construction, and other advantages which will sufficiently appear from the following description of a preferred form of embodiment illustrated in the accompanying drawing.

In the drawing:

Figure 1 is a side elevational view of the attachment mounted in operative position on a propeller;

Fig. 2 is a similar view with the trolling plate removed from the propeller;

Fig. 3 is a rear elevational view, on a relatively enlarged scale, showing the attachment mounted in operative position;

Fig. 4 is a smaller scale cross sectional view taken on the line 4—4 of Fig. 3; and

Fig. 5 is a view similar to that of Fig. 4 showing the manner in which the trolling plate is attached and detached.

In the drawing the reference character 1 designates a propeller of any conventional type commonly used with motorboats. As shown, this propeller is part of an outboard motor assembly 2 having the customary rudder fins 3, 3, but it is to be understood that the propeller may be of any other type and the assembly may be made differently, either inboard or outboard. The details of

2

the propeller and its drive form no part of the present invention.

Broadly speaking, the invention includes a propulsion-retarding baffle in the form of a plate which has a plurality of apertures receiving terminally enlarged shoulders formed on arms or the like which are permanently mounted on the propeller. The plate is attached to the propeller by slipping the arm enlargements through the plate apertures, and the plate is then held in fixed position by interposing an obstruction between it and the shoulders so that the plate cannot slip off the arms by movement in a reverse direction from that by which it was applied to them.

In the preferred embodiment of the invention illustrated in the drawing the arms which are permanently carried by the propeller are made as part of a fixture 4. This fixture includes a base plate portion 5 centrally apertured to receive the threaded end of the propeller shaft 6 and be held thereon by the usual nut 7 which is present for the purpose of holding the propeller hub 8 on the shaft. The base 5 has a plurality of arms 9, preferably three in number, turned rearwardly from the edges of the base and projecting substantially parallel to the axis of the shaft and substantially equidistantly around it, and terminating in enlargements or shoulders 10 at the free ends of the arms. In the illustrated embodiment of the invention these enlargements comprise short reversely bent portions of the arms. They may be made otherwise. They may be formed simply as right angularly bent flanges, or they may be thickened lugs or securely affixed pins. In any event they present forwardly facing abrupt shoulders.

The fixture 4 thus forms a sort of cage or spider which is permanently secured by the nut 7 to the propeller shaft and remains there during normal operation of the propeller. In such operation the fixture rotates with the shaft and produces little if any retarding effect on the propeller effort.

The attachable trolling plate assembly includes principally a plate 11 which may be circular in shape and of any size and area desired. The plate has arranged equidistantly around its center point a plurality of apertures 12, each large enough and properly located to pass one of the enlargements or shoulders 10, so that the plate can be slipped onto the fixture 4 by forward axial movement from the dotted line to the full line position shown in Fig. 5.

The plate assembly includes means for locking the plate on the fixture. Satisfactory locking

means may take any of a number of forms but, according to the principles of the present invention, an essential feature of each form is the interposition, between the plate and each enlargement 10, of means covering enough of each opening 12 to prevent passage of the enlargements 10 therethrough.

The preferred locking means comprises a disc 13, best made circular in shape and having a circumference large enough to place the outer marginal portions of the disc in obstructing position between the enlargements 10 and the openings 12, as best appears in Fig. 4. In this position, assuming the disc is kept from lateral shifting in the plane of its surface, the plate 11 is kept from slipping rearwardly off the fixture 4. Forward movement of the plate, toward the propeller 1, is not prevented by the disc, but in actual practice the pressure of the stream from the propeller prevents such forward movement and the result is a secure positioning of the plate at the outer extremity of the fixture 4, as shown in Figs. 1 and 4.

If, as is preferred, the arms 9 are made three or more in number, lateral shifting of the disc 3 is prevented by the engagement of the arms with the periphery of the disc, as shown in Fig. 3. Pressure from the propeller stream need not be relied upon as the sole force holding the plate 11 in its position shown in Fig. 4 if, as is preferred, the arms 9 be made slightly resilient and rearwardly flaring so that they are inherently biased into engagement with the radially outer margins of the openings 12. By such construction the arms frictionally hold the plate in its rear or operative position, as shown in Fig. 4, quite independently of operation of the propeller. Indeed, the engagement may be and preferably is made sufficiently tight to permit the propeller to be reversed (which can be done with most inboard motors, although it is not common for outboard motors to be equipped with reversing gear) and the boat to be run astern at any moderate speed without causing pressure of the water from the rear to push the plate 11 toward the propeller. However, the frictional fit is not too tight to keep the plate from being manually slid back on the arms to the full line position of Fig. 5. A very convenient relationship of the arms, plate and locking disc is provided by making the circumference of the disc great enough to expand the arms positively into engagement with the radially outer margins of the openings 12 when the parts are in operative position as shown in Fig. 4. In this way the locked arrangement can be made very secure.

The disc 13 is best made captive on the plate 11 and movable to and from its locking position as shown in Fig. 4. All of this is conveniently effected by mounted a pin 15, in the form of a common type of bolt, so as to project rearwardly from the plate 11. This pin stands through a diametrical slot 16 formed in the disc, wide enough to pass the shank of the pin but too narrow to pass the head 17 of the pin. The slot permits the disc to be rocked relatively to the pin to assume the inclined position shown in Fig. 5. The disc can be tilted to this position when its movement is not prevented by the shoulders 10, i. e., when the plate 11 and disc 13 are moved on the fixture 4 toward the propeller, as shown in full lines in Fig. 5. In this position of the parts the disc 13 can be set edgewise between the shoulders 10 so that those shoulders will not prevent passage of the disc between them. In

this way the disc and the plate can be slipped off the fixture by moving them from the full line position of Fig. 5 to and beyond the dotted line position thereof, and thus the plate is removed from the fixture.

The plate is mounted on the fixture by positioning the parts in the same way and passing the enlargements through the openings 12 to the full line position of Fig. 5. Thereupon the disc 10 is rocked to a plane parallel to that of the plate 11, behind the shoulders 10, and the plate is moved to its dotted line position of Fig. 5, into engagement with the disc 13, and the parts are thus securely held in operative position, as has been explained.

The fixture, plate and disc may all be made of sheet metal, and of course these parts should be made corrosion resistant by suitable plating or by selecting non-ferrous stock.

It is to be understood that the broad principles of the invention are capable of being modified from the specific, although preferred, embodiment which has been illustrated and described. It is also to be understood that not all the features of construction which have been specified hereinabove need be used together in each practical embodiment, since some of them are optional. The spirit of the invention is defined by the appended claims.

I claim:

1. An attachment for connecting a trolling plate to a propeller shaft comprising a plurality of arms adapted to project rearwardly from the shaft and each having a transversely extending shoulder formed on its free end for passing a perforation in the plate to mount the plate on the arms, and a locking disc adapted to be interposed between each shoulder and the plate for obstructing passage of the shoulders through the perforations and thereby holding the plate on the arms.

2. An attachment for connecting a trolling plate to a propeller shaft comprising a fixture adapted to be secured to the shaft and having a plurality of terminally enlarged arms projecting rearwardly for passing perforations in the plate to mount the plate on the fixture, and a movable locking disc having portions adapted to be interposed between the plate and the enlargements for obstructing passage of the enlargements through the perforations and thereby holding the plate on the fixture.

3. An attachment for connecting a trolling plate to a propeller shaft comprising a fixture adapted to be secured to the shaft and having a plurality of arms adapted to be substantially equally spaced around the axis of the shaft and to extend substantially parallel thereto, a shoulder formed on the free end of each arm for passing a perforation in the plate and thereby mounting the plate on the fixture by penetration of said arms and shoulders through said perforations, and a locking disc positioned between the plate and shoulders for obstructing passage of the shoulders through the perforations and thereby fixing the plate on the fixture.

4. An attachment for connecting a trolling plate to a propeller shaft comprising a plurality of arms adapted to project rearwardly from the shaft and each having a transversely extending shoulder formed on its free end for passing a perforation in the plate to mount the plate on the arms, a locking disc interposed between the plate and the shoulders, and means connecting the disc to the plate for tilting movement between a posi-

tion in which the disc lies in a plane radial to the shaft and engaging the shoulders and plate to obstruct passage of the shoulders through the perforations and thereby hold the plate on the arms and a position in which the disc is inclined relatively to the shaft axis so that the margins of the disc may be passed between the shoulders to permit the plate to be withdrawn from the arms.

5. A trolling plate attachment as claimed in claim 4 in which the means connecting the disc to the plate comprises a pin projecting rearwardly from the plate extending through a substantially diametrical slot in the disc and having a head holding the disc captive on the pin.

6. A trolling plate attachment as claimed in claim 4 in which the arms are formed on a fixture and are substantially equidistantly spaced around said axis.

7. A trolling plate attachment as claimed in claim 4 for a shaft which has a threaded end and in which the arms are formed on a fixture having a centrally apertured base adapted to receive the shaft and to be held thereon by a nut engaging the threaded end of the shaft and are substantially equidistantly spaced around said axis.

8. A trolling plate attachment as claimed in claim 4 for a shaft which has a threaded end, in which the arms are formed on a fixture having a centrally apertured base adapted to receive the shaft and to be held thereon by a nut engaging the threaded end of the shaft and having

5 said arms extending from the base and substantially equidistantly spaced around said axis, and in which the means connecting the disc to the plate comprises a pin projecting rearwardly from the plate extending through a substantially diametrical slot in the disc and having a head holding the disc captive on the pin.

10 9. An attachment for connecting a trolling plate to a propeller shaft comprising a plurality of arms adapted to project rearwardly from the propeller and flaring slightly outwardly from the propeller axis, a forwardly facing shoulder formed on the rear end of each arm for passing an aperture in the plate, and a locking disc adapted to be interposed between the plate and the shoulders to expand the arms into engagement with the margins of the apertures in the plate and to obstruct said apertures to prevent passage of the shoulders therethrough, thereby holding the plate against rearward movement off the arms.
